F. ROGNLIE

TRENCH MORTAR

Filed March 19, 1923

Inventor
Fred Rognlie
By Munro & Co.
Attorneys

UNITED STATES PATENT OFFICE.

FRED ROGNLIE, OF CHURCHS FERRY, NORTH DAKOTA.

TRENCH MORTAR.

Application filed March 19, 1923. Serial No. 626,137.

To all whom it may concern:

Be it known that I, FRED ROGNLIE, a citizen of the United States, and a resident of Churchs Ferry, in the county of Ramsey and State of North Dakota, have invented a new and useful Improvement in Trench Mortar, of which the following is a full, clear, and exact description.

My invention relates to improvements in portable guns used for artillery work in warfare, especially for trench work, and it consists in the combinations, constructions, and arrangements herein described and claimed.

An object of my invention is to provide a gun which can be used individually, or which can be used in connection with other guns of similar construction, means being provided for interlocking the barrels of adjacent guns, so that the battery thus formed will have the guns at the same inclination, thus enabling them to fire very closely to the same location.

A further object of the invention is to provide a battery of interlocking guns of the type described, in which the spinning or rotating effect on the gun itself, caused by the rifling of the guns, is diminished or counteracted by providing adjacent guns with rifling, running in the reverse direction; that is to say, by providing one gun, for instance, with a right hand spiral rifling, and the gun next to it with a left hand spiral rifling. This causes the battery to remain steady while giving the full rotative effect to the shells which are fired by the guns.

A further object is to provide a battery of trench mortars, in which the batteries of the mortars or guns are interlocked, as stated, but in which each individual gun has freedom to recoil independently of other guns, thereby reducing the liability of damage to the guns of the battery.

A further object of my invention is to provide a battery of the guns of the type described, having means for quickly adjusting the angle of elevation, and hence the range of the guns, so as to give accurate fire.

A further object of the invention is to provide a battery of breech loading guns in which the breech block of each gun is locked in position by its connection or attachment with the adjacent gun, thus insuring the locking of the breech.

Other objects and advantages will appear in the following specification, and the novel features of the invention will be particularly pointed out in the appended claims.

My invention is illustrated in the accompanying drawings, forming part of this application, in which—

Figure 1 is a side elevation of a gun constructed according to my invention,

Figure 2 is a section along the line 2—2 of Figure 1, looking in the direction of the arrows.

Figure 3 is a perspective view showing a pair of guns in locked relation,

Figure 4 is a rear view of the gun, and

Figure 5 is a section along the line 5—5 of Figure 2.

In carrying out my invention, I make use of a gun barrel, such as that shown at 1. Toward the front of the barrel and on one side thereof is a boss 2 which is provided with a dovetail tongue 3 extending therefrom. The rear of the gun is provided with a similar boss 4 with a dovetail-shaped tongue 5. The breech block 6 is also provided with a boss 7, having a tongue 8 of similar shape. The bosses 4 and 7, together with their tongues 5 and 8, are adapted to be brought into registration by means of the engaging shoulders at 9 in Figure 1.

As will be seen from Figures 2 and 5, the breech block 6 may be screwed into the breech of the barrel 1. The screw thread is so designed that the block 6 may be removed from the barrel by a one-eighth turn of the block.

On the opposite side of the barrel is a boss 10 which is in alinement with the boss 2 and which is provided with a groove 11 of a shape to receive the dovetail-shaped tongue, of an adjacent gun, corresponding to the tongue 3. A boss 12, having a similar groove 13, is provided on the side opposite from the boss 4.

Each gun is provided with rifling, such as that shown at 14 in Figure 2, adapted to give the shell 15 a rotary movement about its axis to insure true flight.

In Figure 3, I have shown a pair of these mortars or guns mounted in battery form. It is obvious that as many units may be joined together as is necessary or desirable. In this figure, the gun barrels A and B are mounted on base plates A' and B', these base plates resting on the ground and being con-

tiguous to each other, but not being connected together. The barrels of the guns A and B are connected together by inserting the tongues 3 and 4 of one gun into the 5 grooves 11 and 13 of the adjacent gun, and bringing the two guns into position on their base plates, so as to cause substantial registration of the bosses. Each gun is supported by rods, such as those shown at (a) and (b) 10 respectively. Turn buckles or other means of adjustment (t) are provided so that the elevation of the guns may be readily effected. The guns are preferably fired by detonators of any suitable type, and are designed to be set off by electrical means. To 15 this end the wires (w) are provided.

From the foregoing description of the various parts of the device, the operation thereof may be readily understood. The breech 20 block 6 is removed from the gun by turning the block one-eighth of a turn, the shell 15 is inserted, and the block is then turned until the shoulders 9 engage one another, thereby bringing the tongues 5 and 8 into registration. The two guns are then secured together in the manner described, and this locks the breech block through the engagement of the tongues 5 and 8 with the slot 13. The guns may be elevated by placing the inclined supporting rods (a) and (b) at the proper angle, and then a further adjustment may be effected by means of the extension members from the turn buckles (t). 30

The battery thus formed may be fired by 35 an electrical circuit through the wire (w). The rifling of the adjacent barrels in opposite directions tends to reduce the rotative effect of the gun, while permitting the full rotative effect to be imparted to the shell. 40 Should one of the guns have a greater recoil than the other, this would be permitted through the sliding engagement of the locking means, without damage to the guns.

While I have shown a battery of two 45 units, it is obvious that as many units may be used as desired, and that the guns will be kept in alinement.

I claim:

1. A trench mortar comprising a barrel, a 50 removable breech block, and means carried by the breech block for connection with an adjacent gun.

2. A trench mortar comprising a barrel having a boss, a removable breech block 55 having a boss, the boss in the barrel and in

the breech block each having a groove arranged to register with the companion groove, when the breech block is in firing position.

3. A trench mortar comprising a barrel 60 having laterally extending connecting means, a removable breech block, means carried by the barrel for connection with an adjacent gun barrel, and means carried by the breech block for connection with an adjacent gun. 65

4. A battery comprising a plurality of trench mortars, each mortar having a barrel, means carried by the barrel for interlocking with the adjacent barrel, a removable breech block and means carried by the breech block 70 for interlocking with an adjacent gun.

5. A battery comprising a plurality of trench mortars, each mortar having a barrel, means carried by the barrel for interlocking with the adjacent barrel, a removable breech block and means carried by the breech block 75 for interlocking with an adjacent gun, said interlocking means also locking the breech block to its individual gun.

6. A battery comprising a plurality of 80 trench mortars, means for interlocking the barrels of said mortars to prevent lateral movement and to permit individual longitudinal movement of each barrel.

7. A battery comprising a plurality of 85 trench mortars, the barrels of adjacent mortars having interlocking means for preventing lateral movement, while permitting longitudinal movement, and a removable breech block carried by each mortar, said breech block being locked by the interlocking of the barrels of adjacent mortars. 90

8. A battery comprising a plurality of trench mortars, the barrels of said mortars being disposed in parallel relation, means 95 carried by the barrels for interlocking them to prevent lateral movement, and means for supporting and for elevating said barrels to the desired degree.

9. A battery comprising a plurality of 100 trench mortars, the barrels of said mortars being disposed in parallel relation, means for interlocking the barrels to prevent lateral movement, while permitting independent longitudinal movement of each barrel, 105 the adjacent barrels being rifled in opposite directions, whereby the rotative effect on one barrel is neutralized by the adjacent barrel.

FRED ROGNLIE.
